Des. 212,609
Patented Nov. 5, 1968

212,609

FISHING PLUG

Paul C. Lott, 2974 Cheyenne Drive,
Owensboro, Ky. 42301

Filed Jan. 10, 1968, Ser. No. 10,114

Term of patent 14 years

(Cl. D22—27)

FIG. 1

FIG. 3

FIG. 2

FIG. 4

FIG. 1 is a view in side elevation of the fishing plug, where the opposite side is a mirror image thereof;

FIG. 2 is a view in front elevation of the claimed design;

FIG. 3 is a top plan view of the claimed design of FIGS. 1 and 2; and,

FIG. 4 is a bottom plan view of the claimed design of FIGS. 1 and 2.

I claim:

The ornamental design for a fishing plug, as shown and described.
